(57) **CLAIM**

The ornamental design for a right-handed measuring tape with a sliding magnifier, as shown.

DESCRIPTION

FIG. 1 is a top perspective view of a right-handed measuring tape;

FIG. 2 is a bottom perspective view thereof;

FIG. 3 is a top view of a first section thereof;

FIG. 4 is a top view of a second section thereof;

FIG. 5 is a top view of a third section thereof;

FIG. 6 is a bottom view of a first section thereof;

FIG. 7 is a bottom view of a second section thereof; and,

FIG. 8 is a bottom view of a third section thereof.

The broken lines are for illustrative purposes only and forms no part of the claimed design.
